Application September 30, 1940, Serial No. 358,998

7 Claims. (Cl. 93—3)

This invention relates to the manufacture and filling of containers and bags. The embodiment herein described is particularly directed to the novel method of packaging tea, coffee and similar essence containing products, such packages being made and sold as complete articles of manufacture for use in brewing beverages, as for example, so-called tea-balls. Bags forming said tea-balls are herein described as being constructed of heat sealing filter sheet material, the manufacture of a suitable sheet material for such tea-balls being described in the application of Theodore F. Menzel, Serial No. 335,694, filed May 17, 1940.

Among the objects of the invention is to generally improve the manufacture of filled packages of the character described which shall be capable of being utilized inexpensively and in a simple and easy manner for large scale production yet of neat and attractive appearance, and which shall be efficient and practical to a high degree.

Other objects of this invention will in part be obvious and in part hereinafter pointed out.

The invention accordingly consists in the features of the method, and steps of the process exemplified in the method hereinafter described, and of which the scope of application will be indicated in the following claims.

In the accompanying drawings in which possible illustrative embodiments of the invention are shown:

Fig. 1 is a diagrammatic view illustrating a manufacturing method of tea-balls or the like embodying the invention.

Fig. 2 is an end view, partly in section, showing the cutting of the filter sheet material into unit sections and the partial bag forming operation (dotted lines) in improved manufacturing of the tea-ball bags from a web or strip taken from a roll. Fig. 2a is a cross-sectional view taken on line 2a—2a in Fig. 2.

Figs. 3, 4 and 5 are end, side and top views, respectively, showing the heat sealing operation of the longitudinal seam for forming a tubular unit section of the tea-ball bag.

Fig. 6 is a side elevational view showing the tubular bag unit section formed with the heat sealed longitudinal seam finish.

Fig. 7 is a cross-sectional view taken on line 7—7 in Fig. 6.

Fig. 8 is a side elevational view showing the heat sealing of the bag bottom closure and filling operation.

Fig. 9 is a cross-sectional view taken on line 9—9 in Fig. 8.

Fig. 10 is a cross-sectional view showing the operation of heat sealing of the filled bag top closure.

Fig. 11 is a cross-sectional view showing the handle stapling operation at the superimposed portions of the longitudinal seam and the filled bag top closure.

Fig. 12 is a front elevational view of a finished pillow-shaped tea-ball manufactured by the method embodying the invention, and

Fig. 13 is a cross-sectional view taken on line 13—13 in Fig. 12.

Referring in detail to the drawings, in Fig. 12, 20 denotes a complete pillow shaped tea bag manufactured by the method embodying the invention, said tea bag 20 being provided with a string handle 21 which is anchored by suitable means such as a staple 22 in the manner hereinafter described, said string handle 21 being terminated at its free end with a tag 23.

The successive individual steps illustrating the improved method of manufacture of tea balls 20 embodying the invention are shown in Figs. 2, 3, 6, 8, 10 and 11. In practising said method it is contemplated making said tea ball 20 with bags made of suitable sheet material 24 which may be supplied from a roll R or other suitable source. Said sheet material 24 may be fed from said roll R in the form of a web or strip of the required width, said sheet material 24 being of a suitable foraminous structure, as for example being formed of a base layer 24a of suitable filter paper, perforated parchment paper, cotton gauze or perforated Cellophane, said base layer 24a being superficially coated on one surface thereof with an adhering thermosetting "partially fused" lamina 24b of the character described in the above-mentioned Menzel patent application without substantially decreasing the original porosity of the base layer 24a. Any other suitable heat sealing filter sheet material may be used provided that such material will withstand immersion in hot water without damage or disintegration and which permits ready passage therethrough of liquids for forming a brew and strains the contents T, such as tea or coffee, on passage of the brew out of the ball 20. The base layer 24a with the coating lamina 24b when used as sheet material 24 should be of such compositions that they are insoluble in hot boiling water, do not impart the slightest degree of odor or taste to the brew, have no chemical action therewith, and are absolutely free from giving the brew the least harmful toxic effect when used as a beverage.

The strip or web of the sheet material 24 with the coated lamina 24b as it continuously comes off the roll R may be fed along a flat surface support F with the coated lamina 24b facing inward in the direction towards a hollow mandrel M or other suitable former and centrally aligned with said hollow mandrel M as shown in Fig. 2. It is then cut by blades B into unit sections 25 of required length for making the bag structure of the tea ball 20. As here shown, the surface support F immediately over the mandrel M is channeled or slotted to permit the passage of the mandrel M with the cut bag unit section 25 so that said unit section 25 is partially wrapped about the mandrel M as indicated in dotted lines in Fig. 2. As the mandrel M with unit section 25 passes beyond the channel, the section unit 25 is completely wrapped around the mandrel M and the opposite free outwardly extending edge portions thereof are pressed together and heated to the fusion temperature of the thermosetting plastic coating lamina 24b by suitable means as for example by clamp heater C thereby forming the longitudinally extending seam 25a as shown in Figs. 3, 4 and 5.

In the art of tea-ball manufacture a method for producing same to be of any commercial utility must be readily adapted to incorporation in the operation of automatic machinery so that low cost large scale production is made possible. To that end there is shown in Fig. 1 diagrammatically illustrated such application of automatic operation. The steps in such operation may take place if desired through the use of uniformly spaced, radially extending rotatable mandrels M. The steps of cutting and forming the strip into section units providing the longitudinal seam taking place at stations I and II and during the passage of a mandrel M from stations I and II.

After the longitudinal seam 25a is formed at station II it may be folded over against the tubular body formed of said unit section 25 as shown at 25b in Figs. 6 and 7. The mandrel M at station II or during the rotation thereof from station II to station III has the seamed tubular section drawn along the mandrel M and beyond the end thereof a sufficient distance to permit applying a bottom closure 26 and positioning the bag structure 27 then formed for filling. Suitable means, as for example indicated in dotted lines by grip fingers G as shown in Figs. 6, 8 and 9 for such operation may be used, the mandrel M being formed with cut away portions M1 to clear said fingers G and facilitate the operation thereof. The outer end portions of the bag unit section which form the bottom of the bag are then pressed together and heat sealed in permanent adhesion by suitable means such as another clamp heater H to form said continuous bottom cross seam 26 and joining the lower end of the longitudinal seam 25b of the section unit 25 so that said latter seam 25b extends centrally down one flat side of the bag structure 27 thus simultaneously formed as shown in Figs. 8 and 9.

As illustrated in Fig. 1, on further movement of the mandrel M from station III or when it reaches station IV, the bag structure 27 carried therewith is filled with a measured quantity of an essence containing product such as tea leaves T, the latter being inserted through the leading end or mouth 21a of the bag structure 27 through the hollow mandrel M from a suitable supply indicated at W. The filled bag section 29a may next be removed from the mandrel M at the

station IV and the portion of the bag adjacent the mouth 21a is next pressed together and heat sealed in permanent adhesion by suitable means such as a clamp heater H1 in a manner similar to forming the bottom seam 26. This forms a continuous top cross outwardly extending top closure seam 29 joining the upper end of the longitudinal seam 25b of the filled bag to provide the filled closed package 29 shown in Figs. 10 and 11.

The filled and closed bag package 29 may next have the string handle 21 attached thereto preferably by having one end anchored by suitable means such as staple 22 to the upper portion of the longitudinal seam 25a which is superimposed over the top closure seam 28 as shown in Figs. 12 and 13. By providing said construction the staple 22 passes through four thicknesses of material and enables the tea ball 20 to be held in suspension by means of the string handle 21 in a balanced position so that any stresses or strains created by handling of the tea ball 20 or during brewing will not tear the bag structure, there being provided a bracing support from the string handle 21 through the staple 22 and the longitudinal seam 25a for the entire suspended tea ball structure.

The pillow-shaped tea ball 20 thus formed confines the tea leaves in a bag of shallow depth and thickness and the longitudinal seam and cross seam arrangement serve as a trim to enhance the attractive appearance of said tea ball. The seams 25a, 26 and 28 also retain the bag structure of the unit sections flat and counteract any tendency for the tea ball bag structure to curl and become unsightly in use.

It is therefore seen that there is provided an improved method in which the several objects of the invention are achieved and which are well adapted to meet the conditions of practical use.

As various possible embodiments of the invention may be made in the above invention and as various changes may be made in the embodiments of the method above set forth, it is to be understood that all matters herein set forth and shown in the accompanying drawings are to be interpreted as illustrative and not in a limiting sense.

Having thus described my invention I claim as new and desire to secure by Letters Patent:

1. The method of manufacturing tea-balls and like articles of the character described comprising steps of forming an open ended tubular structure from a rectangular strip of foraminous sheet material formed of a filter layer base coated with a "partial fused" thermosetting plastic lamina with the latter extending on the interior side thereof by pressing and heating sealing for permanent adhesion abutting lamina coated surfaces of edge portions of said tubular structure to provide a longitudinally extending seam, pressing and heat sealing for permanent adhesion abutting lamina coated surfaces of an open end of said tubular structure to form a bag with a bottom closure seam extending over and joining one end of said longitudinal seam, filling each bag with an essence containing product through the other open end thereof, and pressing and heat sealing for permanent adhesion of abutting lamina coated surfaces of said open end to form a completely sealed brewing package with a top closure seam extending over and joining the other end of said longitudinal seam.

2. The method defined in claim 1 including the step of flattening the bag and extending the

longitudinal seam centrally along a flattened side thereof simultaneously with the forming of said bottom closure.

3. The method defined in claim 1 including the steps of flattening the bag and extending the longitudinal seam centrally along a flattened side thereof simultaneously with the forming of said bottom closure, and stapling a string handle to the completely sealed package at the junction of the longitudinal and top closure seams.

4. The continuous method of manufacturing tea-balls and like articles of the character described comprising steps of forming open ended tubular structures successively from a supply of rectangular strips of foraminous sheet material formed of a filter layer base coated with a "partial fused" thermosetting plastic lamina with the latter extending on the interior side of said structures by pressing and heat sealing for permanent adhesion of abutting lamina coated surfaces of edge portions of each tubular structure to provide a longitudinally extending seam, then pressing and heat sealing for permanent adhesion abutting lamina coated surfaces of an open end of each tubular structure to form a flattened bag with a bottom closure seam extending transverse said longitudinal seam and locating the latter centrally on one flat side of the bag, next filling each bag with a measured quantity of essence containing product through the open end thereof, and then pressing and heat sealing for permanent adhesion abutting lamina coated surfaces of each bag open end to form a completely sealed brewing package with a top closure seam extending transversely over the centralized longitudinal seam.

5. The method defined in claim 4 including the additional successive step of anchoring an end

of a string handle to the multi ply portion of the sealed package on the transversely extending longitudinal seams over said top closure seam.

6. The method of the character described comprising the steps of cutting successive unit sections off one by one from a travelling strip of foraminous sheet material formed of a filter layer base coated on one side with a "partial fused" thermosetting plastic lamina, wrapping each unit section about a mandrel with the coated lamina side thereagainst, heat sealing for permanent adhesion edge portions of each wrapped unit section into a longitudinally extending seam and forming an open ended tubular structure therefrom with said lamina covering the interior surface thereof, drawing an open end portion of said tubular structure to extend beyond said mandrel, heat sealing for permanent adhesion said extended end of the tubular structure with a closure cross seam joining its mid portion with one end of said longitudinal seam to provide a bag, filling each bag with an essence containing product through the mandrel and the open end of the bag, removing the filled bag from the mandrel, heat sealing for permanent adhesion the open end portions of each bag to form a top closure seam joining the other end of said longitudinal seam, and anchoring a string handle to said closure seam through superimposed piles of sheet material forming the longitudinal and top closure seams.

7. The method defined in claim 6 including the step of flattening the bag to extend the longitudinal seam along a flattened side thereof simultaneously with the heat sealing operation of the bottom closure seam.

HANS O. IRMSCHER.
